UNITED STATES PATENT OFFICE.

HORACE T. THOMAS, OF LANSING, MICHIGAN.

DESIGN FOR AN AUTOMOBILE-SEAT CONSTRUCTION.

58,261.

Specification for Design. Patented June 28, 1921.

Application filed February 25, 1921. Serial No. 447,882. Term of patent 7 years.

To all whom it may concern:

Be it known that I, HORACE T. THOMAS, a citizen of the United States, residing at Lansing, in the county of Ingham and State of Michigan, have invented a new, original, and ornamental Design for an Automobile-Seat Construction, of which the following is a specification, reference being had to the accompanying drawing, forming part thereof.

The figure is a perspective view of an automobile seat construction showing my new design.

I claim:

The ornamental design for an automobile seat construction, as shown.

HORACE T. THOMAS.
